UNITED STATES PATENT OFFICE.

FINLAY W. ROSS, OF BIRTLIE, CANADA.

AUTOMATIC SWITCH.

SPECIFICATION forming part of Letters Patent No. 606,392, dated June 28, 1898.

Application filed July 31, 1897. Serial No. 646,669. (No model.)

To all whom it may concern:

Be it known that I, FINLAY W. ROSS, of Bir-
tle, in the Province of Manitoba and Domin-
ion of Canada, have invented certain new and
useful Improvements in Automatic Switches;
and I do hereby declare the following to be a
full, clear, and exact description of the inven-
tion, such as will enable others skilled in the
art to which it appertains to make and use the
same.

The invention relates to a tramway-switch
in which the switch for transferring the cars
from the main line to the side track, and vice
versa, is operated automatically by the move-
ment or passage of the car over the same.

It consists in the combination, with the main
and side track rails, of a movable section in
which the rails are connected to move upon a
single pivot and connected with a sliding rod
or rail interposed between the rails of said
sections and connected with upright levers
adapted to be operated by the movement or
passage of the car over them, as hereinafter
described and claimed.

25 In the accompanying drawings, Figure 1 is
a plan view of a tramway-switch, showing in
full lines the switch in its proper relation to
the rails of the main line and in dotted lines
its position relative to the side-track rails.
30 Fig. 2 represents the same in side elevation,
showing the arrangement of the upright levers
for operating the switch-section, in full lines
to correspond with the full lines of Fig.
1 and in dotted lines to correspond with the
35 dotted lines of said Fig. 1.

11 indicate the fixed rails of the main track,
and 22 the rails of the side track rigidly se-
cured to the ties or other rail-supports in any
usual or preferred manner.
40 3 and 4 indicate the rails of the movable
section, said rails being rigidly connected by
transverse bars 5 in such manner that any
lateral movement of one of said rails will be
imparted to the other. The rail 4 is pivoted
45 at one end, as indicated at 6, so that any move-
ment of the rails of said movable section will
be upon said pivot as the center of movement.

7 indicates a longitudinally-arranged rod
or bar interposed between the rails 3 and 4 of
50 the movable section and moved in loop-guides
8, secured to the cross-ties 9.

10 indicates a link pivotally connected at

one end with the rod 7 and at its opposite end
with the rail 3 in such manner that any lon-
gitudinal movement of the rod 7 imparts a 55
lateral vibration to the movable section of the
rails.

11 and 12 indicate upright levers slotted at
13 to engage laterally-projecting pins 14 on
the sides of the bar 7. These levers are piv- 60
oted—the lever 12 at its lower end to an up-
right 15, secured to the bed of the track, the
lever 11, if desired, passing up through a slot
therein. The lever 11 is pivoted centrally of
its length and has its lower end connected 65
with the pivot on the bar 7 through a pendent
lug or ear 16 thereon, as indicated in Fig. 2,
the arrangement of the levers 11 and 12 being
such that as one lever is vibrated in one di-
rection for moving the rod 7 longitudinally 70
the opposing lever will be moved in the op-
posite direction.

The car moving over a road constructed as
described will be provided with a pendent
hook or lever under control of the motorman 75
by means of which he is enabled to engage
the projecting ends of the levers for oper-
ating the movable section of rails. Supposing
the car to be moving to the left on the main
track, as indicated in the drawings, and it is 80
desired to switch the car from the said main
track to the siding, (indicated at 22,) by throw-
ing the lever or hook down into engagement
with the lever 12 the rail-sections 34 will be
vibrated from a position in alinement with 85
the rails 11 to one in alinement with the rails
22 of the side track, thereby switching the
car from the main line to the side track or
line. As the car moves onward on said track
it comes in contact with the lever 11, and, 90
vibrating the latter, which has been thrown
forward by the action of the bar 7, and acting
thereon, vibrates the movable section back
again into alinement with the rails 11 of the
main track. Supposing the car to be coming 95
from the opposite direction from the side
track, the hook or lever on the car under the
control of the driver or motorman first comes
in contact with the upright lever 11 and act-
ing upon the rod 7 swings the movable sec- 100

tion of the rail into alinement with the rails
22 of the side track, thereby adapting the
car to be transferred from the side track to
the main line or track. This operation brings

the lever 12 again into position to be operated by the car in passing, and as the rod or bar 7 is moved by the lever 12 the movable section is again brought into alinement with the 5 rails of the main track.

By the arrangement described a very simple and effective switch arrangement is provided and one which is rendered automatic in its 10 action by the proper adjustment of the pend-
10 ent lever or hook under control of the motor-
man.

Having thus described the invention, what I claim as new, and desire to secure by Letters Patent, is—

15 1. In a tramway-switch, the combination with the main and side track rails, of a movable section of track, the two rails of which are rigidly connected to move on a single pivot, an interposed longitudinally-sliding 20 rod connected to said section, and levers con-

nected to said rod to be acted upon by the moving car for operating it and said pivoted section, substantially as described.

2. In a tramway-switch, the track-rails thereof having a movable section in which 25 the two rails are rigidly connected to move on a pivot at one end of one rail of said section, in combination with a sliding rod intermediate the rails of said section and linked thereto, and upright levers adapted to be op- 30 erated by the passing car for opening and closing the switch, substantially as described.

In testimony whereof I have signed this specification in the presence of two subscr-
ing witnesses.

FINLAY W. ROSS.
